(57) **CLAIM**

The ornamental design for an indicator module for positioning proximity sensors, as shown and described.

DESCRIPTION

FIG. 1 is a perspective view of an indicator module for use in positioning proximity sensors, illustrating a new design in accordance with the present invention;

FIG. 2 is a side elevation of the module of FIG. 1;

FIG. 3 is a front elevation of the module of FIG. 1;

FIG. 4 is another side elevation of the module of FIG. 1;

FIG. 5 is a top view of the module of FIG. 1; and,

FIG. 6 is a bottom view of the module of FIG. 1.

The features of the sensors and connectors shown in phantom lines are for illustrative purposes only and form no part of the claimed design.
